KNIFE MECHANISM FOR SHINGLE STRIP APPARATUS

Donald A. Cumfer, Chicago, Ill., assignor to Asphalt Process Corporation, New York, N. Y., a corporation of New Jersey

Application July 25, 1932, Serial No. 624,514

10 Claims. (Cl. 164—28)

This invention relates to devices for cutting slots in roofing material in the formation of shingle simulating strips.

The invention is illustrated in this application as applied to a machine of the type shown and described in the patent to Harry D. Cumfer and Owen D. McFarland, No. 1,257,321 dated Feb. 26, 1918. It is to be understood, however, that the invention is not limited in its application to this or any other particular type of machine or apparatus but that it may be applied with advantage to mechanisms of various forms for cutting slots in roofing material.

Mechanisms for cutting slots in roofing material in the manufacture of shingle simulating strips have comprised a substantially U-shaped slot cutting knife and a carrying block or support formed integral with the knife and adapted to be bolted or otherwise secured to the knife carrier of the mechanism. The knife and support were originally made of tool steel and were therefore expensive to manufacture. Later a process was devised by which the knife and support were made from drop forgings. The grinding to which the knives are subjected in order to maintain the same sufficiently sharp to perform satisfactory work quickly wears down the knives to a condition in which they are unfit for further use. When this occurs the knife with the knife support formed integral therewith are thrown away. This is obviously a wasteful and expensive procedure.

The principal objects of the present invention are to improve the construction of devices for cutting slots in sheet roofing material in the formation of shingle simulating strips and to produce a construction for such devices in which it shall not be necessary to throw away the knife support with the knife and to provide a new knife support and knife when a knife has been rendered unfit for further use.

With the above object in view a feature of the present invention consists in the provision of a construction in which the knife is removably mounted on the support and means is provided for removably securing the knife in position with relation to the support. With this construction, when a knife is worn out the knife may be removed from the support and a new knife may be secured in position on the support. The securing devices and the devices for locating the knife with relation to the support are constructed so that the removal of a knife and the securing of a new knife in place may be

effected quickly and easily by the operator or by an ordinary mechanic.

The above and other features of the invention will be clearly understood from the accompanying drawing illustrating the invention in its preferred form and the following detailed description of the construction therein shown.

In the drawing, Fig. 1 is a view in vertical section of a machine for cutting slots in roofing material having the invention applied thereto; 10

Fig. 2 is a detail view in vertical section taken substantially on the line 2—2 of Fig. 1;

Fig. 3 is a detail perspective view illustrating a knife support and a knife in place thereon, both detached from the knife carrying roller; 15

Fig. 4 is a detail sectional view taken substantially on the line 4—4 of Fig. 3 and

Fig. 5 is a detail sectional view taken substantially on the line 5—5 of Fig. 3

The machine illustrated in Figs. 1 and 2 is of the same general type as that illustrated and described in Patent No. 1,257,321 referred to above. The machine comprises opposed cooperating slitting rollers 2 and 4 between which the sheet roofing material is passed, said sheet being drawn from a roll 6 of the material mounted on a spindle 8. The slitting rollers slit the sheet material into a series of relatively narrow strips. 20

The strips of sheet material pass from the slitting rollers between the knife carrying roller 10 and the opposed roller 12 cooperating with the knife carrying roller. Upon the knife carrying roller are mounted a series of slot cutting knives which cut transverse slots in the strips, the strips being held against the knives by the roller 12. 25

The strips are fed forward by the action of the opposed feed rollers 14, these rollers drawing the material past the slitting rollers and the rollers 10 and 12. 30

The knife carrying roller 10 carries a series of knives indicated at 16. Each of these knives is formed in one piece and has the shape shown in Figures 3 to 5 inclusive. As shown in these figures, the body 16 of the knife is bent into the form of an elongated O, the ends 18 of the knife body being in abutting relation. The knife is formed with a substantially U-shaped cutting blade 20 which cuts correspondingly shaped slots in the strips of roofing material. The blade is formed with substantially parallel side portions for cutting the sides of a slot and with a curved portion connecting the side portions for cutting the end of the slot. 45

The knife is removably mounted upon a sup- 50

55

port indicated at 22. The support consists of a block having a series of holes 24 therein through which are passed screws 26 for securing the same to the knife carrying roller. The knife support is formed with a recess 28 having substantially the same shape and size as the outside of the body of the knife into which the knife is arranged to fit as shown particularly in Figures 3, 4 and 5. This recess is provided at its base with an abutment or shoulder 30 against which the inner edge of the knife rests when in position on the support. The knife is removably secured in place on the support by means of a series of screws 32 passing through openings in the support and threaded into the body of the blade.

By means of the above construction the knives are removably held securely in position on the respective knife supports. A knife may be quickly and easily removed from its support and another knife may as quickly and easily be secured in operating position on the support without removing the support from the roller 10.

It will be noted that the parallel side portions of the knife are connected by an integral curved portion of the knife and that the ends 18 of the knife body are in abutting relation when the knife is secured in place on the support. By reason of this construction the holding screws 32 are relieved, to a large degree of strain.

It is to be understood that the invention is not limited to the particular construction and arrangement of parts of the illustrated embodiment of the invention but that the construction shown is merely illustrative of the invention and that the invention may be embodied in various other forms within the scope of the claims.

What is claimed as new is:

- 40 1. In a device for slotting sheet material a knife support having a knife receiving recess, a knife mounted in said recess, said knife having a U-shaped edge portion and a body portion integral therewith, said body having two ends extending respectively beyond the ends of the U into mutually abutting relation, and means for removably securing the knife in the recess.
- 45 2. In a device for cutting slots in sheet material, a knife support having an abutment for the rear edge of the knife, a knife having substantially parallel side cutting blades and an end cutting blade and a body common to said blades, said knife being mounted on said support with its rear edge engaging said abutment, said body having portions extending beyond said parallel blades at the ends thereof remote from the end blade and having the ends of said extensions abutting, and means for removably securing the knife in place on the support.
- 50 3. In a device for cutting slots in sheet material a knife support, a slot cutting knife removably mounted on said support, said knife being formed of one piece with the confronting ends of the piece in strain resisting mutually abutting relation when so mounted in said support.
- 55 4. In a device for cutting slots in sheet material, a knife support, a one piece knife having blades for cutting the sides of a slot and a blade for cutting one end of the slot, said knife having a portion formed for fitting engagement with

said support and provided with two ends mutually abutting in strain-resisting relation when the knife is in fitting engagement with said support, and means for removably securing said knife in position on the support.

5 5. In a device for cutting slots in roofing material a knife support, an elongated O-shaped knife removably mounted on the support, said knife being formed in one piece with the ends of the piece mutually abutting to close the O and in strain-resisting relation, and means for securing the knife in position on the support.

6. In a device for slotting sheet material, a knife support having a knife receiving recess shaped to receive an elongated O-shaped knife 15 and provided with an abutment for engagement with the rear edge of the knife, an elongated O-shaped knife in one piece removably mounted in said recess with its rear edge engaging said abutment, said O-shaped knife forming an annulus parted at one point in the circumference thereof to form ends of the piece having end surfaces transversely to the circumference of the annulus and abutting each other, and means for securing the knife in position on the support.

20 7. A knife for cutting holes in sheet material, said knife being formed as an annulus from one piece of material having two ends with said two ends of the piece confronting each other and meeting in the annulus in strain resisting mutually abutting relation.

25 8. A knife for cutting holes in sheet material, said knife being formed as an annulus from one piece of material having two ends with the end faces of said two ends of the piece meeting in 35 a plane transverse to the annulus in strain-resisting mutually abutting relation.

9. In combination with a cutting roller for cutting slots in a continuously delivered sheet of material, a knife formed of one piece having a 40 pair of blades extending generally parallel to each other and a blade transversely of said parallel blades, said blades providing a continuous cutting edge, said knife having a body portion formed for fitting engagement with a 45 recess in said roller, said recess being so formed as to position said parallel blades generally parallel to the axis of the roller, said body portion of said knife adjacent one end of the parallel blades being formed with two ends having end 50 faces mutually abutting in a plane generally parallel to said parallel blades and in strain-resisting relation.

55 10. In combination with a cutting roller for cutting slots in a continuously delivered sheet of material, a knife support removably attached to said roller and having a knife receiving recess therein, a knife formed of one piece having a pair of blades extending generally parallel to each other and a blade transversely of said parallel blades, said blades providing a continuous cutting edge, said support being so mounted upon said roller that said parallel blades extend generally parallel to the axis of the roller, said knife having a body portion formed for fitting engagement with said support when mounted in said recess and formed with two ends adjacent one end of the parallel blades 60 mutually abutting in strain-resisting relation when the knife is mounted in said support.

65 70. DONALD A. CUMFER.
